TRAY INSERT FOR A FURNITURE DRAWER

Joseph R. Sander, University City, Mo., assignor to
H. Robert Industries, Inc., St. Louis, Mo., a corporation of Missouri

Filed Oct. 27, 1966, Ser. No. 4,440

Term of patent 14 years

(Cl. D33—1)

FIG. 1

FIG. 2

FIG. 3

FIGURE 1 is a plan view of a tray insert for a furniture drawer, embodying my new design.

FIGURE 2 is a front elevation thereof.

FIGURE 3 is a left end elevation thereof.

FIGURE 4 is an enlarged fragmentary view of the right end of FIGURE 2, the left end being the mirror image thereof.

The undisclosed sides of the tray are plain and unornamented.

The design is characterized by broad horizontal flanges on the opposing side edges and rear edge, the side flanges having narrow parallel grooves, the rear flange having parallel grooves extending between the grooves of said side flanges, all as shown.

I claim:

The ornamental design for a tray insert for a furniture drawer, substantially as shown and described.
